ASSIGNORS TO NORTON COMPANY, OF WORCESTER, MASSACHUSETTS, A CORPO-
RATION OF MASSACHUSETTS.

GRINDING MACHINE FOR FORMING ROLLS.

Application filed May 21, 1921. Serial No. 471,413.

To all whom it may concern:

Be it known that we, HANS WICKSTROM and PATRICK J. SHEA, citizens of the United States of America, residing at Worcester, 5 in the county of Worcester and State of Massachusetts, have invented certain new and useful Improvements in Grinding Machines for Forming Rolls, of which the following is a full, clear, and exact specification.

Our invention relates to grinding machines for forming rolls, and more particularly to machines having the roll forming attachment shown and described in an application of C. H. Norton, Serial No. 435,098, filed Jan. 5, 1921.

In the machine referred to, it is proposed to form rolls on the well known form of plain cylindrical grinding machine, such 20 as is disclosed in the patent to Norton No. 762,838 dated June 14, 1904, in which the work is mounted on a swivel table which is in turn mounted on a sliding table to reciprocate it past the wheel. To effect such 25 a forming action, it is there proposed to arrange follower members adjacent one end of said tables, between which there extends a longitudinally stationary tapered forming bar, the followers being held against the 30 forming bar under the action of a spring. From this arrangement it will be obvious that as the tables reciprocate, the swivel table will be swung on its pivot as it follows the shape of the bar to form the roll.

It is obvious that this bar will have to be very accurately formed to produce the exact form of roll desired, and if made to form theoretically accurate rolls, in practice it is found that the bar will frequently have 40 to be re-scraped or ground, due to the inherent characteristics of the machine in which it is to be used, in order to produce a roll of the exact shape desired. This scraping to get the exact form of bar required is of course a slow and tedious operation. Furthermore, it becomes necessary to supply a separate bar for each form of roll it is desired to grind on any particular machine, which involves considerable expense 45 and delay in changing the bar. Since a bar can be used only on the particular machine for which it is fitted, its use is further limited by this consideration.

It is therefore an object of our invention

to overcome these difficulties by making the 55 forming bar itself adjustable in thickness at a plurality of points along its length so that its form can be readily and quickly changed to suit the machine on which it is to be used and to adapt it to grind rolls of 60 different forms.

Referring to the accompanying drawings, in which like reference characters indicate like parts:

Figure 1 is a front elevation of a machine 65 equipped with the forming attachment with which our improved forming bar is adapted to be used;

Fig. 2 is a plan view of the work table 70 of the machine shown in Fig. 1;

Fig. 3 is an enlarged fragmentary sectional view through the roller-carrying brackets, lower table and base, showing the forming bar in section in its position between the rollers, the section being taken 75 approximately on the line 3-3 of Fig. 4;

Fig. 4 is a fragmentary plan of parts shown in Fig. 3;

Fig. 5 is a plan view of the forming bar, parts being broken away, and Fig. 6 is a 80 similar view on an enlarged scale to more clearly show the means for adjusting the bar.

In the specific embodiment of our invention selected for illustration, we have shown 85 our device applied to a grinding machine of the type shown in the patent above referred to, and in which the work table 1 is mounted to slide longitudinally on the usual ways on the base 2 and is provided with the 90 usual means for traversing it either by hand or automatically, as is fully described in said prior patent. In Fig. 3 we have shown only the hand traversing means, which consists of a rack 3 rigidly connected to the 95 under side of the table 1 and driven from the hand wheel 4 through the gearing 5, shaft 6 and pinion 7, the latter engaging the teeth of the rack. On the table 1 is mounted the transversely movable table 10 which may 100 be of the usual swivel construction, the pivot being indicated at 9 (Figs. 1 and 2). On the table 10 are mounted the headstock 11 and tailstock 12 which may be of any suitable construction for supporting and rotating 105 the work. Where the work comprises a heavy roll 13 having end bearings 14, we preferably support it in work supports

15 with or without the use of the tailstock and rotate it by having its squared end 16 engage a similarly shaped opening 17 in a driven member 18 on the headstock 11. We 5 have shown the latter as being motor driven in a manner similar to that shown in the patent to C. H. Norton No. 1,152,434 dated September 7, 1915. We do not desire to be limited to the specific manner of supporting 10 and rotating the work which is merely illustrative and forms no part of the present invention.

In order to effect a relative transverse movement between the tables 1 and 10 while 15 the work is traversing past the grinding wheel 19 to give the desired form to the work, we provide opposed follower members such as the rollers 20 and 21 between which is supported a forming bar 22 of de- 20 sired configuration and these rollers are held against the opposite sides of the bar by any suitable means such as the spring 23. In the present instance we have shown our device adapted for crowning rolls and the 25 rollers are arranged adjacent one end of the tables while the table 10 is swivelled as at 9. The forming bar may be tapered from end to end. It is supported by a block 25 (Figs. 3 and 4) between the rollers and a 30 bracket 26 (Fig. 1) extending upwardly from the base. The bar is pivoted to this bracket to allow swinging movement thereof. We may connect the bar as by screws 28 to a short arm 29 which is in turn pivoted 35 at 27 to the bracket 26.

In order to avoid the necessity of carrying 40 a number of bars with each machine where it is desired to grind rolls with different heights of crown, for example, on the same machine, we make the forming bar 22 adjustable in width, and we may accomplish this by the construction shown in 45 Figs. 3 to 6. We have there shown the forming bar as being split, as by means of a saw cut 31, substantially from end to end (see Figs. 5 and 6) and as being provided at a point intermediate its ends and preferably at frequent intervals along its length with 50 push and pull screws 32, 33 arranged in pairs. Dowel pins 34 are also provided at different points along the length of the bar to hold the split parts of the bar in suitable opposed relation. It will be understood 55 that the screws 33 for pulling the split portions of the bar together have their heads 35 arranged in countersunk recesses so as to be at all times below the surface on which the rollers travel while the push screws 32 are also at all times below the surface of the 60 bar. These pairs of push and pull screws can be arranged at suitable intervals along the bar, and we have found that spacing them about 4 inches apart will make provision for a very accurate adjustment of the 65 bar. By this arrangement the bar can be

given any desired width at the various points along its length within operative limits, thus permitting a ready adjustment for any spring of the table or for other causes of inaccuracies in the form of the 70 roll, and for grinding rolls of different form on the same machine.

The rollers are preferably mounted, as described in the application to C. H. Norton above referred to, on substantially vertical 75 pivots arranged in opposed relation at the right-hand end of the tables as shown in Figs. 1 and 2. The inner roller 20 is located in a downwardly opening recess 36 formed in a bracket 37 which is preferably removably secured to the end of the swivel table 10 as by screws 38. A headed stud 39 supports the roller and serves as a pivot pin therefor. We have shown this stud securely held as by set screws 40 in a hole in the 80 bracket 37. The outer roller 21 is shown supported in a bracket 41 suitably connected to the table 1. We have shown it formed integrally with the table to provide a rigid 85 construction and to render its manufacture 90 easy. An upwardly opening recess 42 is provided in this bracket to receive the roller 21 and a hole is provided in the bracket below said recess and opening thereinto to receive the lower end of the stud 44 on which the roller is pivoted. The upper end of 95 said pin extends into a hole 45 formed in a top plate 46 closing the recess in the bracket and secured thereto by screws 47.

It may be desirable, under certain conditions, to effect a slight lateral adjustment of one of the rollers 20 or 21. We have provided a construction in which the axis of the roller 21 is made adjustable and we conveniently accomplish this adjustment by 100 making the part 48 of the stud 44 on which the roller is pivoted eccentric to the end portion, by extending the upper end portion beyond the top plate 46, and forming it with a squared portion 49 for engagement with a suitable tool for rotating it. Rotation of the stud will obviously shift the axis 105 of rotation of the roller 21. We may provide this stud between the squared portion 49 of the top plate 46 with a tapered collar 50 provided with graduations 51 cooperating with a suitable index 52 on the top plate for indicating the amount of lateral movement of the roller axis and consequently of 110 the end of the swivel table. When once adjusted, the stud is locked in place by suitable clamping screws 53.

In the operation of our machine, supposing that it is desired to grind a roll with a given amount of crown and so that the surface of the roll is curved uniformly from end to end, a templet or forming bar 22 is 115 adjusted by the screws 32, 33 to give it a substantially straight taper from end to end. The table 1 is first moved to bring 120

- one end of the roll, let us say the left-hand end, Figs. 1 and 2, opposite the grinding wheel and the grinding wheel is fed into contact with the roll by the usual feeding mechanism indicated at 61, Fig. 1. If the roll is cylindrical and its axis is parallel with the path of reciprocation or the ways of the table 1 when the grinding wheel is opposite the longitudinal center of the roll, then with the parts in the position first supposed, the left-hand end of the roll is nearer to the grinding wheel axis than the right-hand end. As the table is traversed to the left from this position, the swivel table is swung by the tapered bar until the work axis is parallel to the table ways when the wheel is opposite the center of the roll and from there on the roll axis will incline in the opposite direction to the table ways until the wheel again touches the roll at the right-hand end. The grinding is then continued until the wheel has ground the entire surface of the roll and the roll has reached the desired dimensions. If the roll axis should happen to be slightly out of alignment with the table ways, and this can be determined by caliper the opposite ends of the roll after they have both been ground to some extent, in which case they will be of different diameters, it will be necessary to effect some adjustment to bring about correct alignment. This is conveniently accomplished in our device by applying a wrench to the squared portion of the stud on which the roller 21 is eccentrically pivoted and moving the pivot either toward or away from the axis of the roll as may be required to effect the necessary alignment.
- If it is found that the roll does not have the desired shape due to the spring of the table or from other causes, the forming bar is adjusted to correct such inaccuracies in form of the roll and this can be very quickly done by my improved construction. It will be seen then that we have provided a very simple and convenient device for adapting the forming bar to the inherent characteristics of different machines, or for adapting it to the same machine under different conditions of operation, such as would be met with grinding rolls of different sizes and with different heights of crown.
- While we have shown our improved forming device used in connection with the specific machine disclosed and claimed in the application above referred to, it is obvious that changes may be made in the specific construction of our device and that equivalent elements may be substituted for parts herein disclosed without departing from the scope of our invention as expressed in the claims appended hereto.
- Having thus described our invention, what we claim as new and desire to secure by Letters Patent is:
1. A grinding machine having relatively reciprocating work and wheel supports, one of said supports being also movable transversely during reciprocation to form the work, a follower on said transversely movable support, a forming bar against which said follower is held during reciprocation, and means to position the bar and hold said bar and follower in engagement during reciprocation, said forming bar having means for adjusting its width at a point intermediate its ends. 60
  2. A grinding machine having relatively reciprocating work and wheel supports, one of said supports being also movable transversely during reciprocation to form the work, a follower on said transversely movable support, a longitudinally divided forming bar against which said follower is held during the reciprocation, means for adjusting the width of the bar at a plurality of points along its length, and means to position the bar and hold the bar and follower in contact during reciprocation. 80
  3. A grinding machine comprising a base, a reciprocating table thereon, a transversely movable work-carrying table mounted thereon, a follower on each of said tables, and means including a forming bar held against longitudinal movement and extending between said followers to move the tables relative to each other as they reciprocate, said bar being adjustable in width at a plurality of points along its length. 90
  4. In a machine for grinding cylindrical work, a forming bar split in a plane at right angles to its operative surface, and means for adjusting the width of the bar and for holding it in adjusted position. 100
  5. In a machine for grinding cylindrical work, a forming bar split in a plane at right angles to its operative surface, means for adjusting the width of the bar at a plurality of points along its length and for holding it in adjusted position comprising push and pull screws arranged in pairs, and means for holding the split portions of the bar in opposed relation. 110
- Signed at Worcester, Massachusetts, this 20th day of May 1921.
- HANS WICKSTROM.
